UNITED STATES PATENT OFFICE.

PETER KAISER, OF CROWN POINT, INDIANA, ASSIGNOR OF SIXTY-FIVE ONE-HUNDREDTHS TO CLAYTON D. ROOT, OF CROWN POINT, INDIANA.

INCUBATOR.

1,190,419.

Specification of Letters Patent.

Patented July 11, 1916.

Application filed October 14, 1915. Serial No. 55,818.

To all whom it may concern:

Be it known that I, PETER KAISER, a citizen of the United States, and a resident of Crown Point, in the county of Lake and 5 State of Indiana, have invented certain new and useful Improvements in Incubators, of which the following is a full, clear, and exact specification.

My invention is concerned with incubators, and is designed to produce a device of the class described in which the thermostat connections and devices by which the temperature of the heating fluid is kept uniform shall be of the simplest possible nature, and 15 hence very durable and not liable to get out of order.

To illustrate my invention, I have annexed hereto two sheets of drawings, in which the same reference characters are used to designate identical parts in all the figures, of which,—

Figure 1 is a top plan view of the incubator with the cover removed; Fig. 2 is an end elevation of the same; Fig. 3 is a view 25 in section on the line 3—3 of Fig. 1, but on a slightly enlarged scale; Fig. 4 is a vertical section on a still larger scale, on the line 4—4 of Fig. 3; and Fig. 5 is a plan view in section on the line 5—5 of Fig. 4.

30 In carrying out my invention in its preferred form, I employ the customary hollow casing 10, in which is mounted the egg tray 11, and which is provided with a preferably removable cover or top 12. The casing may 35 be of any desired construction, and is preferably supported by the adjustable and removable legs 13.

In the upper portion of the casing, where 40 my invention is to be employed in connection with an incubator of the hot-water circulating type, I place the pair of rectangular pipes 14 and 15, each of said pipes being connected at one end with the horizontal supply-tube 16, and at the other end to the 45 horizontal discharge-tube 17 located above the same. These tubes 16 and 17 pass through suitable apertures in the adjacent wall of the casing, and are connected to the boiler 18, which has the plurality of vertical 50 tubes 19 extending therethrough, so that the heat from the lamp can pass upward through said tubes and heat the water in the boiler 18. I preferably provide the boiler with a passage 20 to one side thereof, 55 through which the waste heat can pass when

the thermostat operates to deflect some of the heat arising from the lamp 21. This lamp 21 may be of any customary construction, and it is preferably provided with the spring clips 22 by which the lamp may be 60 quickly and conveniently secured upon the flange 23 formed on the short sleeve or collar 24, which is supported from the bracket 25 secured to the adjacent side of the casing.

The short sleeve 24 terminates at about 65 the point where the flame from the lamp rises, and on the outer surface of this sleeve I pivot the flue 25, which is preferably composed of metal, and which may be of the general shape of the customary lamp 70 chimney. This flue 25 is preferably rounded in cross section at its lower end, while its upper end is shaped so that it is substantially square in cross section, and said upper end enters the rectangular bottom opening 75 of the boiler extension 26, which will be seen to consist of a metal shell having its flaring upper end adapted to be closed by the boiler and the associated passage 20 for the waste heat. The sides of this boiler extension 80 26 converge toward the bottom, as clearly seen in Figs. 2 and 3, and I preferably provide the partition 27 therein, as shown in Figs. 4 and 5. The upper end of the flue 25 preferably flares a trifle, as seen 85 at 28 in Fig. 4, and is preferably also provided with an extension 29 which operates as a stop against the partition 27 when the flue is in its vertical position and all the heat is passing up through the boiler 18. 90 To counterbalance the flue and hold it normally in its vertical position, and to enable it to be swung steadily, I preferably provide the counterbalance weight 30, which is preferably secured on the outer end of the 95 arm or lever 31, the inner end of which is fastened to the flue, as clearly shown in Fig. 4.

Within the casing 10, I secure the bracket 32, and upon this bracket I support, by a 100 pivot or otherwise, the thermostat disk or element 33, the upper or free portion of which engages the lever 34, preferably by being pivoted thereto. This lever 34 is of the second class, and is fulcrumed to a bearing 35, preferably formed in the bracket 32. The load end of the lever 34 extends out through a narrow slot 36 in the casing, and is connected by the link 37 with the arm or 105 lever 31.

With the connections noted, it will be seen that as the temperature rises, the thermostat element tends to swing the outer end of the lever 34 upward, and this, acting through the link 37 and the arm 31, tilts or swings the flue 25 toward the dotted-line position shown in Fig. 1. If the temperature rises much, it is thrown entirely over to the dotted-line position, in which all the heat from the lamp is deflected through the waste passage and lost. With this arrangement, the heating fluid will cool and bring the temperature back to the desired degree, and as it cools, the thermostat element 33 contracts and the flue 25 swings back under the action of the counterbalance weight 30.

To conveniently and accurately regulate the temperature at which the thermostat shall act, from the exterior, I thread the upper end of the link 37 and pass it through an aperture in the outer end of the lever 34, and provide the set nut 38 by which the effective length of the link 37 can be adjusted. If further adjustment of the length of the link 37 is deemed necessary, I may thread the lower end and secure it to the arm 31 by the set nuts 39.

While I have shown and described my invention as embodied in the form of incubator which I consider best adapted for its purposes, it will be understood that it can be applied to other forms and that it is capable of some modifications.

What I claim as new, and desire to secure by Letters Patent of the United States, is:

1. In a device of the class described, the combination with a casing having heat-distributing appliances therein and a thermostat element fixedly supported therein, of a lamp supported outside of the casing, a chimney on said lamp consisting of a fixed collar portion closely surrounding the lamp burner, and a main portion pivoted near the top of the collar portion and overlapping and making a comparatively tight joint therewith in all positions, a heat-applying member above the chimney having heat-utilizing passages extending therethrough, and link and lever connections from the thermostat element to the swinging portion of the chimney so that the expansion of the thermostat under undue heat will swing the chimney so as to deflect some of the heat from the heat-utilizing passages.

2. In a device of the class described, the combination with a casing having heat-distributing appliances therein and a thermostat element fixedly supported therein, of a lamp supported outside of the casing, a chimney on said lamp consisting of a fixed collar portion closely surrounding the lamp burner, and a main portion pivoted near the top of the collar portion and overlapping and making a comparatively tight joint therewith in all positions, a heat-applying

member above the chimney having heat-utilizing passages extending therethrough, a bracket support for the thermostat element within the casing, a single lever fulcrumed on the bracket and connected to the free side of the thermostat element and having its load arm extending outside of the casing, and a link extending from the load arm and connected to the swinging portion of the chimney at a distance from its fulcrum.

3. In a device of the class described, the combination with a casing having heat-distributing appliances therein and a thermostat element fixedly supported therein, of a lamp supported outside of the casing, a chimney on said lamp consisting of a fixed collar portion closely surrounding the lamp burner, and a main portion pivoted near the top of the collar portion and overlapping and making a comparatively tight joint therewith in all positions, a heat-applying member above the chimney having heat-utilizing passages extending therethrough, a bracket support for the thermostat element within the casing, a single lever fulcrumed on the bracket and connected to the free side of the thermostat element and having its load arm extending outside of the casing, and a link extending from the load arm and connected to the swinging portion of the chimney at a distance from its fulcrum, and a counterbalance weight on the swinging portion of the chimney tending to hold it in its heating position.

4. In a device of the class described, the combination with a casing having heat-distributing appliances therein and a thermostat element fixedly supported therein, of a lamp supported outside of the casing, a chimney on said lamp consisting of a fixed collar portion closely surrounding the lamp burner, and a main portion pivoted near the top of the collar portion and overlapping and making a comparatively tight joint therewith in all positions, a heat-applying member above the chimney having heat-utilizing passages extending therethrough, a single lever fulcrumed within the casing and connected to the free side of the thermostat element and having its load arm extending outside of the casing, an arm fixed to the swinging portion of the chimney, a counterbalance weight on the outer end of the arm, and a link connecting the lever and arm.

5. In a device of the class described, the combination with a casing having heat-distributing appliances therein and a thermostat element fixedly supported therein, of a lamp supported outside of the casing, a chimney on said lamp consisting of a fixed collar portion closely surrounding the lamp burner, and a main portion pivoted near the top of the collar portion and overlapping

and making a comparatively tight joint therewith in all positions, a heat-applying member above the chimney having heat-utilizing passages extending therethrough, 5 a single lever fulcrumed within the casing and connected to the free side of the thermostat element and having its load arm extending outside of the casing, an arm fixed to the swinging portion of the chimney, a 10 counterbalance weight on the outer end of the arm, a link connecting the lever and arm, and means for adjusting the effective length of the link, consisting of a nut threaded on the upper end thereof and engaging the lever through which it passes.

6. In a device of the class described, the combination with a casing having heat-distributing appliances therein, of a lamp supported outside of the casing, a chimney on 20 said lamp consisting of a fixed collar portion closely surrounding the lamp burner, and a main portion pivoted near the top of the collar portion and overlapping and mak-

ing a comparatively tight joint therewith in all positions, a heat-applying member 25 above the chimney connected with the heat-distributing appliances and having heat-utilizing passages extending therethrough, a bracket support within the casing, a thermostat element supported thereon, a single 30 lever fulcrumed to the bracket and connected to the free side of the thermostat element and having its load arm extending outside of the casing, an arm fixed to the swinging portion of the chimney, a counterbalance weight on the outer end of the arm, 35 and a link connecting the lever and arm, substantially as and for the purpose described.

In witness whereof, I have hereunto set 40 my hand and affixed my seal, this 8th day of October, A. D. 1915.

PETER KAISER. [L.S.]
